SCREENING ATTACHMENT FOR COAL-WAGONS.

1,129,994.

Specification of Letters Patent.

Patented Mar. 2, 1915.

Application filed April 17, 1914. Serial No. 832,498.

To all whom it may concern:

Be it known that I, JOHN R. LAWRENCE, a subject of the King of Great Britain and Ireland, residing at Sarnia, in the Province 5 of Ontario and Dominion of Canada, have invented certain new and useful Improvements in Screening Attachments for Coal-Wagons, of which the following is a specification, reference being had therein to the 10 accompanying drawings.

The invention relates to screening devices and has for its particular object the provision of means for screening coal without the necessity of an additional handling. In 15 the present state of the art it is usual in coal yards to screen the coal immediately preceding the loading of the same into the wagon. This generally requires the co-operation of two laborers, one shoveling the 20 coal upon the screen and the other transferring the screened coal to the wagon. With my improved construction the work may be performed by a single man, who shovels the coal into the screening attachment, from which it passes directly into the 25 wagon.

In the drawings: Figure 1 is a cross section through a wagon to which my improvement is applied; and Fig. 2 is a perspective 30 view of the attachment removed from the wagon.

A is a casing provided with sides B and a screen bottom C extending between said sides.

35 D is a hopper-shaped receptacle above the screen having a restricted mouth or discharge opening E adjacent to the screen.

F is an apron or tubular chute, preferably formed of a flexible fabric and attached to 40 the casing A so as to surround the screen C and depend therefrom.

G are hooked-shaped bearings attached to the lower end of the casing A adapted to rest upon the side-board H of the wagon 45 box I.

J are tie connections attached to the upper end of the casing and adapted to be secured to the opposite side of the wagon box, as indicated at K so as to hold the casing in an 50 inclined position, shown in Fig. 1.

With the construction as described, the apron or cloth chute F may be connected with a suitable box or receptacle for holding the screenings, and the operator then shovels the coal into the hopper D, from 55 which it passes downward over the screen C. This will separate out the dust, which falls through the chute F, while the screened coal will fill the wagon box. The device can be quickly shifted from one wagon to another, 60 and thus the wagons may be successively filled with screened coal without increasing the labor over that required for filling them with unscreened coal.

What I claim as my invention is:— 65

1. A device for the purpose described, comprising a casing including a screen bottom and a hopper above said screen adapted to discharge the material fed into said hopper on to said screen, said casing having 70 hooked bearings at its lower end engageable with the sides of a receptacle, and tie connections with the opposite side of said receptacle for holding said casing in inclined position, and a flexible apron surrounding 75 and depending from the screen for receiving the screenings, said screen being so positioned that the larger pieces will be discharged into the receptacle.

2. A device for the purpose described, 80

comprising a casing including a screen bottom and a hopper above said screen adapted to discharge the material fed into said hopper on to said screen, said casing having 85 hooked bearings at its lower end engageable with the sides of a receptacle, and tie connections with the opposite sides of said receptacle for holding said casing in inclined

position, said screen being so positioned that the larger pieces will be discharged into the 90 receptacle and the smaller pieces outside thereof.

In testimony whereof I affix my signature in presence of two witnesses.

JOHN R. LAWRENCE.
